United States Patent Office.

GERARD SICKELS, OF BOSTON, MASSACHUSETTS.

Letters Patent No. 96,356, dated November 2, 1869.

IMPROVED FOLDING BEDSTEAD.

The Schedule referred to in these Letters Patent and making part of the same.

To whom it may concern:

Be it known that I, GERARD SICKELS, of Boston, in the county of Suffolk, and State of Massachusetts, have invented a new and useful "Folding Bedstead," of which the following is a full, clear, and exact description, reference being had to the accompanying drawings, in which—

Figure 1 is a perspective drawing of the folding bedstead, embodying my invention.

Figure 2 is a bottom view of the folded bedstead, looking up from below the same.

Figure 3 is an end view of the same.

Figure 4 are details.

The object of my invention is to produce a bedstead which can be folded up, and firmly held in that position, without removing any parts therefrom, and which, by two simple movements, can be made ready again for use. Thus a bedstead can be put up, and be stored away without taking it in pieces, and be always complete and ready; and

My invention consists in a bedstead which can be folding into a compact form, and held together by the use of the devices hereinafter described.

Referring to the drawings—

A is the head, and

B, the foot-board of the bedstead.

The side-rails C C' are provided, respectively, with joints at a b c a' b' c', the middle joints b b' being also connected with suitable legs and casters d d', for supporting the rails C C', and for facilitating the operation of folding.

To the portions of C C', which are rigidly attached to the head and foot-boards, are fastened cross-pieces

D D', to which is hinged the bed-bottom, consisting of the two rails E E' and the cross-slats F F' F", &c; the rails E E' being each formed of two pieces, of equal lengths, hinged together, respectively, and to the cross-pieces D D' in such a manner as to be doubled up upward, by moving the head and foot-boards toward one another.

The operation of raising the bed-bottom is facilitated by the brackets G, which, together with brackets G', support the rails E E' when extended.

To the under side of the cross-pieces D are attached, with one end, the bars h h', the other end of which is provided with a grooved head, which fits on cams i i', attached to cross-piece D' in such a manner that when the bedstead is being folded, and the bars h h' are pushed outwardly, they will tighten on cams i i', and thus hold the bedstead securely folded; and when moved inwardly, they will relax their grasp, and thus allow the bedstead to be drawn out.

Having thus fully described my invention,

What I claim as new, and desire to secure by Letters Patent, is—

The head and foot-boards A B, folding rails C C', and upwardly-folding bed-bottom, in combination with bars h h', brackets G G', and cam-blocks i i', in the manner and for the purpose substantially as described.

In testimony whereof, I have signed my name to this specification, in the presence of two subscribing witnesses.

GERARD SICKELS.
